(57) **CLAIM**

The ornamental design for a charging hub for a motion capturing system, as shown and described.

DESCRIPTION

FIG. 1 is a top perspective view of a charging hub including a communication dongle and an array of sensors exploded therefrom according to our new design.

FIG. 2 is a bottom perspective view of the charging hub including the communication dongle and the array of sensors exploded therefrom of FIG. 1.

FIG. 3 is a top plan view thereof.

FIG. 4 is a bottom plan view thereof.

FIG. 5 is a left-side elevation view thereof. A right-side elevation view is identical to the left-side elevation view thereof.

FIG. 6 is a front elevation view thereof. A rear elevation view is identical to the front elevation view thereof; and, FIG. 7 is a front elevation view thereof. A rear elevation view is identical to the front elevation view thereof.

Broken lines illustrate the communication dongle and the array of sensors that form no part of the claimed design.

1 Claim, 6 Drawing Sheets
